ABRASIVE ARTICLE

Douglas T. Peden, Ann Arbor, Mich., assignor to
 Micromatic Hone Corporation, Detroit, Mich.,
 a corporation of Michigan

Application January 28, 1949, Serial No. 73,416

5 Claims. (Cl. 51—184.3)

1

This invention relates to improvements in abrasive articles, and more particularly to honing stones for producing accurate and finely finished surfaces, and is a continuation-in-part of Serial No. 499,472, filed August 21, 1943, and assigned to the assignee of the present invention.

While the invention is broadly applicable to the regulation of wear of such abrasives, it is more directly concerned with its use as a means for efficiently gauging the size of a workpiece during the operation of this type of honing stone thereon.

The primary object of the invention is to afford a practical adjunct to the method of gauging of the type disclosed in U. S. Patent No. 2,398,356, issued January 12, 1943, which was assigned to the assignee of the present invention. It is, nevertheless, to be understood that the invention is not to be restricted to such use as is evident from the objects of the present invention which are: to provide nonabrasive portions on a honing abrasive of a character which will wear consistent with the wear of the abrasive and be suitable for contacting a gauging means without abrading the latter; to retard the rate of "break-down" or wear of the abrasive under circumstances of extreme pressure application, from whatever source, without interfering with its normal wear rate; to afford stability to abrading members, particularly those of relatively small working area, when they are in contact with the workpiece; to augment the tensile strength of abrading members so as to avoid their shattering under vibration or chattering conditions of operation, and to provide an economical and practical means for mounting hone abrasives and prolong their service life.

Other objects and advantages of this invention will become apparent from the following description taken in connection with the accompanying drawing, in which:

Figure 1 is a perspective view of a honing abrasive embodying features of this invention;

Fig. 2 is a sectional view of the structure illustrated in Fig. 1, taken on the line 2—2 thereof;

Fig. 3 is a view of structure, similar to that illustrated in Fig. 1, showing another form of the invention;

Fig. 4 is a sectional view of the structure illustrated in Fig. 3, taken on the line 4—4 thereof;

Fig. 5 is a view in elevation of a tool and abrasive elements employed in conjunction with a gauge member which indicates the moment the cylinder has been machined to size;

Fig. 6 is a sectional view of a short abrasive stone and supporting element by which it is applied to a workpiece; and

2

Fig. 7 is a perspective view of a tool with the honing abrasives illustrated in Figs. 3 and 4 disposed therein.

In the aforementioned U. S. Patent No. 2,308-356, titled "Gauging method and means," a caliper or measuring device is disclosed which directly measures the size of the tool during its operation on a workpiece. This was also a measure of the bore which could be finished to any desired dimension. The abrading members of the honing tool were arranged to directly contact the gauging means at an extremity of the working stroke and indicated when the diameter had been reached. It was found that a slight abrading effect resulted, occurring as a result of the contact of the gauging elements with the abrading material, which necessitated occasional readjustment of the gauging mechanism to compensate therefor.

The present invention obviates the need for the readjustments of the gauging mechanism by virtue of providing nonabrading tabs at the extremities of the abrasive. As illustrated in Fig. 1, this may be accomplished by applying non-abrading inserts at the ends of the abrasive elements 2. The inserts 1 may be composed of phenol or vinyl resinous material, hard rubber, vulcanized fiber, soapstone, sodium silicate, carbon or certain porous metals such as magnesium, aluminum, etc. In fact, any organic or inorganic material which possesses the ability to wear with the abrasive, and yet resist impregnation or "loading" with abrasive particles, may serve as such inserts. The abrasive elements 2 and the nonabrading inserts 1 are adhesively mounted in a metallic backing element 3. Turned-up lugs 4 may be provided at the ends of the element 3 to assist the adhesive to resist the endwise thrust occurring to the element and inserts during operation. Projections 5 extend beyond the lugs 4 for forming a convenient means for receiving a circular garter spring or spring clips which urge the stones inwardly when the honing tool is contracted. In Fig. 2, the element 3 is illustrated as being provided with bosses 6 to prevent endwise movement of the abrasive assembly when it is mounted in the stoneholder of the honing tool. The bosses 6 mate with apertures in the stone-receiving groove of the stoneholder and prevent relative movement therebetween.

In Fig. 3, the five surfaces of the abrasive element 7 are encased in the nonabrading material 8 which forms the nonabrasive engaging portion of the stone assembly having the extended ends 9. The encasing material protects the sides of the

stone from fracture due to chatter or overloading. This type of assembly may be mounted in a stone-holder or be inserted directly in the hone body 31 in direct contact with an expansion cone 32, as illustrated in Fig. 7. The expansion cone 32 is provided with a plurality of grooves 32a each adapted to receive one of the encased stones, the bottom wall 32b of each of the grooves 32a being inclined relative to the axis of the cone 32 so that the stones can be radially adjusted by longitudinal movement of the cone 32 relative to the hone body 31. In this construction, the retaining or garter springs are not required as the frictional contact between walls 33 of the tool body slots and the nonabrading material constituting the casing 3 is sufficient to retain the abrasive assemblies within the hone body 31.

In Fig. 5, a gauging device is illustrated in conjunction with a honing tool having the abrasive elements of Figs. 1 and 2 applied thereto. A supporting bracket 10 retains a sleeve 11 aligned with a honing tool 12 which is reciprocated therethrough. A caliperlike gauging element 13 has inner shoes which are engaged by the abrasive elements 14 which are radially expansible on the tool body. Guide elements 15 of fibre or other material are supported on the tool body between the abrasive elements 14. These guide the tool body in the bore 16 being machined and the aperture 17 in the sleeve 11. A garter spring 18 is employed at the bottom of the tool body 12 in engagement with the projections 5 while individual springs 19 engage the projections at the upper ends of the abrasive elements 14.

Each time the honing tool 12 has stroked to the upper extremity of its travel, contact is made between the gauging element 13 and the nonabrading inserts 1. When the desired work size has been achieved on the abrasive elements 14, the switch 21 will be operated by the next contact between the inserts 1 and element 13. Inasmuch as the nonabrading tabs have contacted the work-piece immediately prior to this instant and have worn to the same height as that of the abrasive elements 2, measurement of the diametric position of the inserts 1 is just as effective as to measure the abrasives themselves. Due to the fact that the tabs are nonabrading in character, no damage or undue wear will occur to the gauging mechanism.

Occasionally, abrasive elements of extremely small working area are used, particularly on work of short length. Such abrasive elements are unstable against thrust loading despite any mechanical counter means which may be provided. This condition is also encountered in workpieces possessing interruptions, such as ports or slots, in the surface to be honed, as illustrated in Fig. 6. Under such circumstances, it is impractical, for reasons of the inaccuracies engendered, to use abrasive elements of sufficient length to span the interruption 23 in the workpiece 24. The present invention makes possible the use of abrasive elements sufficiently short to secure the accuracy desired on work surfaces 25 and still obtain the stability and spanning ability afforded by a long abrasive. This is accomplished by making the abrasive element 26 of the most effectual length and augmenting its length with nonabrading body portion 27 which is of sufficient length to restore stability against the element 26 tilting when force is axially applied to the honing tool when under pressure produced by the movement of the spaced cones 28.

The type of nonabrading material chosen is pre-

dicated upon the character of the abrasive used. For example, hard bonded abrasives may require an insert, or be encased in, a high wear resistant material such as vinyl resin or aluminum. A soft bonded abrasive would respond better if phenol resin or magnesium were used therewith. In any case, it is important that the wear resistance of the insert or encasing material be not greater than that of the abrasive if efficient results are to be obtained.

While the phenol and vinyl resins have satisfactory wearing qualities with relation to the wearing qualities of the abrasive stones, as pointed out above, they are slightly resilient and the substantial pressure applied to the abrasive units by the expansion cone 32 during a honing operation causes the phenol and vinyl materials to slightly compress. As a result, upon the release of the pressure when the cone 32 is retracted, the sides and the end portions 1 and 9 of the units will expand and project slightly beyond the face of the stones 1 and serve to protect the finished honed surface from accident and undesirable marring by the stones upon the continued rotation of the tool as it is being withdrawn from the honed cylinder. This minute expansion of the material at the ends of the abrasive stones is not detrimental to the gauging of the bore upon the operation of the gauging mechanism by the ends 1 and 9 as this slight expansion either is within the degree of accuracy of the diameter tolerance permissible or the amount of expansion, being a constant factor, can be allowed for in setting the gauging mechanism to interrupt the honing operation when the desired size is reached. This slight resiliency of the phenol and vinyl resins aid substantially in the retention of the abrasive elements in the slots when the pressure is removed from the elements, and the materials provide a nonmarring bearing engagement with the slot walls when moved relative thereto.

What is claimed is:

1. A honing element for a honing tool having a body containing slots for the reception of a plurality of said elements and an adjusting member for radially moving said elements outwardly of said body and applying a pressure thereto, said element embodying a bonded abrasive stick of substantial length relative to its width and thickness, and a casing of a relatively nonabrasive material covering said abrasive stick on all surfaces except its working face, said casing being of substantially greater length than said abrasive stick to provide a longitudinally extending tab at each end of said abrasive stick, each of said tabs having a surface substantially in the plane of the working face of said abrasive stick and being of such character as to wear uniformly with the abrasive stick while providing such frictional engagement with the walls of the slots in the tool body, without abrasion of the slot walls, as to frictionally retain the elements on the tool body and within the slots but permitting them to be moved outwardly by the application of a positive force by the adjusting member.

2. A honing element for a honing tool having a body containing slots for the reception of a plurality of said elements and an adjusting member for radially moving said elements outwardly of said body and applying a pressure thereto, said element embodying a bonded abrasive stick of substantial length relative to its width and thickness, and a casing of a relatively nonabrasive material covering said abrasive stick on all surfaces except its working face, the material of said

casing being compressible to a greater degree than said abrasive stick under a given load, said casing being of substantially greater length than said stick to provide a longitudinally extending tab at each end of said stick, each of said tabs having a surface substantially in the plane of the working face of said abrasive stick and being of such character as to wear uniformly with the abrasive stick while providing such frictional engagement with the walls of the slots in the tool body, without abrasion of the slot walls, as to retain the elements on the tool body and within the slots but permitting them to be moved outwardly by the application of a positive force by the adjusting member, the compressibility of said longitudinally extending tabs enabling the same to project a minute amount beyond the working face of the abrasive sticks for preventing the honed finished surface from being marred by the abrasive sticks when the abrading pressure is removed therefrom and the tool is being withdrawn from a honed cylinder.

3. A honing element for a honing tool having a body containing slots for the reception of a plurality of said elements and an adjusting member for radially moving said elements outwardly of said body and applying a pressure thereto, said element embodying a substantially rectangular bonded abrasive stick of a length greater than its width, and a casing of a relatively nonabrasive material adhered to said abrasive stick and covering all of the surfaces thereof except its working face, said casing being of substantially greater length than said abrasive stick to provide a longitudinally extending nonabrading tab at one end of the abrasive stick, said tab having a surface disposed substantially in the plane of the working face of said abrasive stick, said nonabrasive material being of such character as to wear uniformly with the abrasive stick and to provide frictional engagement with the walls of the slots so as to be frictionally retained in the tool body while permitting movement thereof outwardly when a positive pressure is applied to the elements by the adjusting member, said tabs providing for nonabrading engagement with a diameter measuring device as the abrasive sticks are adjusted

outwardly of the tool body to a desired diameter.

4. A honing element for a honing tool comprising a bonded abrasive stick of substantial length relative to its width and thickness, and a casing of a relatively nonabrasive resinous material covering said abrasive stick on all of its sides except its working face, said casing being of substantially greater length than said abrasive stick to provide a longitudinally extending tab at each end of said abrasive stick, each of said tabs having a surface lying substantially in the plane of the working face of said abrasive stick.

5. A honing element for a honing tool comprising a bonded abrasive stick of substantial length relative to its width and thickness, and a longitudinally extending member at each end of the stick having a face disposed substantially in the plane of the working face of the abrasive stick, said member being formed of a resinous material having the property of wearing substantially at the same rate as the abrasive stick and being slightly compressible radially under load so that the said face of each member extends a minute amount beyond the working face of the abrasive stick when the load is released from the element after a honing operation for preventing the working face of the abrasive stick from contacting the finished surface of a honed cylinder when the tool is withdrawn therefrom.
